CLAIM

The ornamental design for protective rings for joysticks, as shown and described.

DESCRIPTION

FIG. 1 is a front and top perspective view of protective rings for joysticks, showing my new design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof; and,

FIG. 7 is an exploded view thereof.

The broken lines in the drawings, depict environmental structure of the protective rings for joysticks that from no part of the claim.

1 Claim, 7 Drawing Sheets
